UNITED STATES PATENT OFFICE.

WILLIS F. HOBBS AND JOHN A. ANDERSON, OF BRIDGEPORT, CONNECTICUT, ASSIGNEES TO THE BRIDGEPORT HARDWARE MANUFACTURING CORPORATION, OF BRIDGEPORT, CONNECTICUT, A CORPORATION OF CONNECTICUT.

VALVE-LIFTING TOOL.

Application filed August 28, 1926. Serial No. 132,090.

This invention relates to valve-spring lifting tools such as are used for compressing the springs of gas engine valves to facilitate removal of the valve, and has for an object 5 to provide an improved construction of tool for this purpose which will be simple in construction, strong and durable, and easily operated.

It is also an object of the invention to 10 provide a device of this character which will comprise a small number of parts so arranged that opposed elements are duplicates of each other so as to reduce to a minimum the number of different parts which must be 15 manufactured, and thus reduce the number of tools and dies required for manufacturing.

It is another object of the invention to 20 provide a simple and effective means for holding the spring-compressing jaws to maintain the springs compressed until the jaws are released.

With the foregoing and other objects in view, we have devised a construction the preferred form of which is illustrated in the accompanying drawing. In this drawing,

Fig. 1 is a top plan view of the tool complete;

Fig. 2 is a side elevation thereof, a portion of one of the handles being broken away to more clearly show the construction;

Fig. 3 is a transverse section substantially on line 3—3 of Fig. 2; and

Fig. 4 is a transverse section substantially 35 on line 4—4 of Fig. 2.

Our improved tool comprises a pair of hand levers 5 pivoted together by means of a rivet 6. These levers each comprises a hand grip 7 and an arm 8 respectively located to 40 the rear and forwardly of the pivot 6, but both on the same side of this pivot. The lever comprises a single piece of metal with the hand grip 7 substantially U-shaped in cross-section and one side being integral 45 with the extension 9 through which the pivot extends and which is integral with the arm 8. When assembled the curved portions connecting the side walls of the grip are on the outside so as to provide a comfortable grip for the hands of the operator. It will be seen that as these levers are 50 reversed when assembled this construction and arrangement allows the use of the same or duplicate structures for both levers and they

may, therefore, be made from the same tools. 55 At the point of the pivot 6 the extension 9 is offset at 10 which offsets engage each other when the levers are assembled giving a better bearing and spacing the remaining portions which cross each other a slight distance so that they do not rub together, and also provide space for the catch 11 for holding the jaws separated.

Pivoted to each of the arms 8 at the free ends thereof is a jaw supporting member 12. 65 This member has a body portion substantially U-shaped in cross-section, and they are arranged with the open sides opposed so that the arm 8 extends between the sides of this U-shaped portion and is pivoted there- 70 to by the pivot 13. Each member 12 carries a jaw 14 which is preferably provided with an open-sided recess 15 for engaging about the valve stems with the jaws between this spring and its abutment in the usual manner. One side of the U-shaped body of the jaw support 12 is extended rearwardly, as shown at 16, to the other side of the pivot 6 from the pivotal connection 18, and this extension is connected by a link 17 to the opposite lever, the link having pivotal connection with the extension at 18 and to the opposite lever at 19. It will be noted that the jaw supporting members 12 are reversed and arranged with their open sides opposed. 75 This allows the use of duplicate structures for the two jaws so that they may be made with the same tools.

It is preferred that the pivots 18 and 19 be substantially the same distance to the rear 80 of the pivot 6 between the levers as the pivotal connections 13 are spaced forwardly of this pivot, so that when the hand grips are pressed together the jaws will be separated and the links 17 during this movement will 85 maintain them in substantially parallel relation. As the links are freely pivoted to the jaw supports and the levers there are no pin and slot connections required between the supports and the levers to allow for 90 relative longitudinal movements as the levers are operated. This makes a very rigid construction which is not liable to work loose and does not wear rapidly in operation.

The catch 11 is provided to hold the jaws 95 in separated relation to prevent their closing under the action of the spring when it is compressed. This catch comprises a lever

pivoted to one of the levers 5, preferably on the same pin or rivet 19 by which a link 17 is pivoted to this lever. At one side edge of the catch is provided with a series of notches 20 adapted to engage a cross-pin 21 in the opposite handle, it being understood that the lever projects into the space between the side portions of this grip. On the opposite side of its pivot this catch lever 19 projects beyond the levers and is bent laterally to provide a thumb-piece 22 for operation to release the catch. A spring 23 mounted within the other hand grip is connected to this lever at 24 at one end and to a struckup lug 25 at the other end in the hand grip. This spring tends to swing the catch clockwise about its pivot, as viewed in Fig. 2, and hold it against the pin 21. The sides of the notches 20 are inclined so that when the hand grips are pressed together to separate the jaws this catch will merely slide over the pin, but the pin will catch in different recesses to prevent movement in the opposite direction until the catch is released by pressure on the thumb-piece 22.

Having thus set forth the nature of our invention, what we claim is:

1. In a device of the character described, a pair of hand levers pivoted together having hand grips extending rearwardly from the pivot and arms extending forwardly from the pivot and located respectively on the same side of the pivot as the corresponding hand grip, a pair of jaw supporting members each pivoted to the free end of one of said arms, and a link fixedly pivoted to each jaw support rearwardly of the pivot and to the opposite lever.

2. In a device of the character described, a pair of hand levers pivoted together each including a hand grip extending to the rear of the pivot and an arm extending forwardly of the pivot and arranged with both said portions of the lever on the same side of the pivot, a jaw support pivoted to each arm and having an extension projecting rearwardly of the pivot, and a link pivoted to said extension to the rear of said pivot in all positions and also to the opposite lever.

3. In a device of the character described, a pair of hand levers pivoted together having hand grips extending rearwardly from the pivot and diverging arms extending forwardly from the pivot, a jaw supporting member pivoted to the free end of each

arm, and a link pivoted to each supporting member and to the opposite lever, both pivots being rearwardly of the pivot between the levers.

4. In a device of the character described, a pair of hand levers pivoted together having hand grips extending rearwardly from the pivot and diverging arms extending forwardly from the pivot located respectively on the same side of the pivot as the corresponding hand grip, a pair of jaw supports each having a body portion of substantially U-shape in cross-section arranged with their open sides opposed and between the sides of which the free ends of said arms extend and to which they are pivoted, and a link pivoted to each support and to the opposite lever, both pivots being rearwardly of the pivot between the levers.

5. In a device of the character described, a pair of hand levers pivoted together having hand grips extending rearwardly from the pivot and arms extending forwardly from the pivot and located respectively on the same side of the pivot as the corresponding hand grip, a pair of jaw supporting members each having a body portion of substantially U-shape in cross-section arranged with their open sides opposed and between the sides of which the free ends of said arms extend and to which they are pivoted, and a link pivoted to each jaw support and to the opposite lever, both pivots being rearwardly of the pivot between the levers.

6. In a device of the character described, a pair of hand levers pivoted together having hand grips extending rearwardly from the pivot and arms extending forwardly from the pivot and located respectively on the same side of the pivot as the corresponding hand grip, a pair of jaw supporting members each pivoted to the free end of one of said arms, a link pivoted to each jaw support and the opposite lever rearwardly of the pivot between the levers, a catch pivoted on the pivotal connection of one of said links to its lever and having holding teeth, means on the other lever to coact with said teeth to hold the levers against relative movement in one direction, and a spring tending to move said catch to holding position.

In testimony whereof we affix our signatures.

WILLIS F. HOBBS.
JOHN A. ANDERSON.
